CLOCK

Nicholas Pitrelli, Brooklyn, N. Y.

Application December 16, 1955, Serial No. 39,356

Term of patent 7 years

(Cl. D42—7)

Fig. 1 is a front elevational view of a clock, showing my new design;

Fig. 2 is a side elevational view of the same; and Fig. 3 is a horizontal sectional view taken on the line 3—3 of Fig. 1.

The dominant features of the design reside in the portion shown in full lines.

I claim:

The ornamental design for a clock, as shown and described.
